UNITED STATES PATENT OFFICE.

CLIFFORD H. BOWERS, OF SAUGUS, MASSACHUSETTS.

SKIRT-BOARD-TONGUE CUTTER.

Application filed October 8, 1924. Serial No. 742,361.

To all whom it may concern:

Be it known that I, CLIFFORD H. BOWERS, a citizen of the United States, and a resident of Saugus, in the county of Essex and State of Massachusetts, have invented a new and useful Improvement in Skirt-Board-Tongue Cutters, of which the following is a specification.

My invention relates to cutting tools and more especially to a tool adapted for cutting tongues in the vertical edges of skirt-boards. Heretofore skirt-boards have been tongued by mallet and chisel, and the operation on the skirt board of the usual stairway requires about an hour.

The object of my invention is to provide a tool whereby a skirt-board or other wooden member may be tongued accurately and rapidly, and with this object in view my invention comprises a cutting blade so related to an adjustable gauge as to produce a tongue of the proper size and shape. The blade has a central straight portion parallel to the face of the gauge and terminates in a side portion curved upwardly with respect to said gauge. Preferably a fine, as well as a coarse, adjustment is provided, although this is not absolutely essential.

By means of my improved-tongue-cutter, the skirt-board of the usual stairway may be tongued in about one-tenth the time required to do the work with a mallet and chisel.

An illustrative embodiment of my invention which has given good results in practice, is shown in the drawings which accompany and form a part of this specification in which—

Figure 1 is a side view of a skirt-board tongue-cutter involving my invention;

Fig. 2 is a plan view of the same;

Fig. 3 is a central longitudinal section;

Fig. 4 is a section of a skirt-board taken on the line 4—4 of Fig. 6;

Fig. 5 is a section of a portion of a riser with the skirt-board in co-operative relation therewith;

Fig. 6 is a fragmentary plan view of a skirt-board;

Fig. 7 is a front elevation of the tongue-cutter shown in Fig. 1.

In the particular drawings selected for more fully disclosing my invention and which are to be considered as illustrative and not restrictive, 10 is a handle of malleable iron or any suitable material carrying

at its forward end a cutting blade 11, the forwardly tapering end 12 of the handle permitting said blade to slope downwardly. While various means may be employed for securing the blade to the handle, I prefer, as shown in the present instance, to clamp the same thereto by means of the nut 13 threaded to the stud 14 which projects from the center of the disc-shaped guide 15, and is threaded to the forward portion 12 of the handle as shown in Fig. 3. A beveled washer, 16 may be interposed between the blade and the nut 13.

The cutting blade has a central straight portion 17 parallel to the face of the gauge 15 and terminating in a side portion 18 curved upwardly with respect to said gauge. Preferably the cutter is made double for right and left skirt-boards, and for this purpose the straight portion 17 of the blade is provided with two upwardly curved side portions 18.

The stud 14 is provided with a thread of fine pitch, for instance twenty threads to the inch, and the depth of the cut will of course be governed by the distance between the cutting blade and the upper face of the disc, which distance may be varied by turning the gauge, a handle 19 preferably being provided for this purpose.

A fine adjustment may be obtained by means of the screw 20 passing through, but not threaded to, the cutting blade and in threaded engagement with the handle, the end of said screw bearing against the upper face of the gauge and preferably taking into one of a plurality of equally spaced depressions 21 therein. In the present instance six such depressions are shown so that by turning the handle one-sixth of a revolution the depth of the cut will be varied one one-hundred and twentieth of an inch.

To cut a tongue in the vertical edges of a skirt-board the operator inverts the latter, sets the gauge for a cut of the proper depth and holds the cutter against the corner formed by a vertical and a horizontal edge of the skirt-board, the side of the portion 12 of the handle serving as a gauge in one direction, and the disc 15 as a gauge in the other, and then pushes the tool across the edge of the board, whereupon a tongue of the shape indicated at 22 in Figs. 4 and 5 will be produced in the vertical edge of the skirt-board 23, the flat portion 17 of said tongue being cut by the central straight

portion 17 of the blade, and the curved portion 18^a of said tongue by the upwardly curved end 18 of said blade.

The riser 24 of the stairway is provided 5 with a groove 25 into which the tongue of the skirt-board is inserted.

Having thus described an illustrative embodiment of my invention without however limiting the same thereto, what I claim and 10 desire to secure by Letters Patent is:—

1. A skirt-board tongue-cutter comprising in combination a handle, a gauge located below the forward end of said handle, a stud projecting from the center of said gauge, a 15 cutting blade arranged on the forward end of said handle, said stud being in threaded engagement with said handle, and passing through a bore in said blade, and a nut threaded to the projecting end of said stud 20 and clamping said blade to said handle.

2. A skirt-board tongue-cutter comprising in combination a handle, a cutting blade

arranged on the forward end of said handle, a gauge located below the forward end of said handle, a stud projecting from the center of said gauge and passing through said handle and blade, and means whereby the plane of the upper face of said gauge may be varied with respect to said blade.

3. A skirt-board tongue-cutter comprising in combination a handle, an adjustable gauge secured to the forward end of said handle, a cutting blade arranged on the forward end of said handle, means whereby the plane of the upper face of said gauge 35 may be varied with respect to said blade and a screw passing through said blade and being in threaded engagement with said handle, the end of said screw taking into a 40 depression in the face of said gauge.

In testimony whereof, I have hereunto subscribed my name this 4th day of October, 1924.

CLIFFORD H. BOWERS.
